KEY COLUMN CLAMP

Filed Oct. 18, 1926

Patented Feb. 19, 1929.

1,702,307

UNITED STATES PATENT OFFICE.

GEORGE F. NEWTON, OF KANSAS CITY, MISSOURI, ASSIGNOR OF ONE-HALF TO SEBASTIAN PATTI, OF KANSAS CITY, MISSOURI.

KEY COLUMN CLAMP.

Application filed October 18, 1926. Serial No. 142,419.

This invention relates to concrete form column clamps and has for its object to produce a key operated clamp which is extremely strong and durable and will positively lock 5 forms which are internally subjected to very high pressures or forces.

Another object is to produce a concrete form column clamp which may be initially clamped in position by means of an external 10 clamp and which when a key is forced home, will further positively draw the parts close together to insure the proper locking of the clamp bars around the form.

A still further object is to produce a simple, strong, durable, efficient and inexpensive 15 concrete column clamp of the character outlined which can be quickly applied in or removed from operative position, and in order that it may be fully understood, reference is 20 to be had to the accompanying drawing, in which:

Figure 1 is a horizontal section taken through a form equipped with a column clamp embodying the invention.

25 Figure 2 is a side elevation of the same.

Figure 3 is an enlarged detail of the method of clamping and locking a corner of the form in position.

30 Figure 4 is a section on the line IV—IV of Figure 3.

Figure 5 is a section on the line V—V of Figure 4.

Figure 6 is an enlarged edge view of one of the locking keys.

35 Figure 7 is a fragmental plan of a modified construction.

Figure 8 is an edge view of a clip disclosed in Figure 7, and adapted for carrying two clamping keys and detachably engaging 40 crossed clamping bars.

Figure 9 is an end view of the clip.

In the said drawing, where like reference 45 characters identify corresponding parts, the clamping mechanism with reference particularly to Figures 1 to 6 inclusive, comprises rectangular bars 1 of any suitable length formed along one of their side edges with a series of clamping teeth 2. Adjacent one of its ends each bar is bent upwardly as at 3 and then continues parallel to its main or body portion as at 4. Riveted or otherwise secured to said end of the bar 1 is a short bar 5, and said bar is also bent slightly as at 6 and continues as at 7 to form a bifurcated 55 portion or clip in conjunction with the part

4, of suitable width to snugly receive the straight end of a similar clamp bar as will be readily understood upon inspection of the drawing. Upon reference to Figure 5, it will be noted that the inclined portions 3 and 6 60 of bars 1 and 5 respectively are internally corrugated in order to form frictional surfaces for engagement with one edge of the straight end of another of the bars being clamped, as will more clearly appear herein- 65 below.

The ends of the clips or parallel parts 4 and 7, are formed with a pair of aligned slots 8 for the sliding reception of locking keys 9. Each key is formed along one of its edges 70 with a hardened knife edge 10 for engagement with the teeth 2 of a bar 1, and is inclined along its other or outer edge, as at 11, for abutment against the outer end of the slots 8, as will be readily understood. It 75 will be understood that the wedge-shaped keys 9 at one end are too large to pass through the slots 8, and in order to prevent them from falling from position in the opposite direction, the smaller ends are crimped as at 12, 80 after they have been placed in position.

After a form has been encircled by four of the clamp bars above described and the corners have been preliminarily tightened, if desired, by the use of any suitable character 85 of cam operating clamp or other mechanism, the operator will lock it in position and will incidentally further tighten the corners by driving the wedges home with hammer blows at the large end of said keys 9. This operation it will be evident, will effect a tightening 90 of the clamps by the wedge action of the knife edge 10 within the key 2 and will positively effect the locking of the form since the bars are frictionally engaged at both of their 95 edges, the inner edge by being tightly pressed against the corrugations internally formed on the inclined portions 3 and 6 of the bars 1 and 5. When it is desired to unlock the form, the operator will strike blows on the 100 lower or smaller end of the keys 9 to drive them upwardly and disengage their knife edges 10 from the teeth 2. If there is any tendency for the rear edges of the bar 1 to be tightly engaged by the corrugations internally formed in the end of the bifurcated portions, the operator will strike a few light 105 blows on the rear or inner edge of said bars 1 to disengage them from said corrugated portions.

The structure as described is preferably modified slightly for use in erecting columns within six inches or so of a wall as is sometimes desirable, as in such case the free end 5 of one of the bars 1 may project too far in the direction of the wall to permit of the necessary adjustment for clamping purposes. For illustration assuming that the column is to be located so close to a building wall that 10 the space will barely accommodate the projecting free end of the right hand bar 1 of Figure 1, in such case, the left hand bar 1, which would project too far and hence against such wall, would be dispensed with and the 15 bar 1^a shown in Figure 7 would be substituted therefor. The bar 1^a may project any desired distance beyond the bar 1 parallel with such wall but at the other side therefrom of the proposed column, as indicated in Figure 7. In this case the teeth 2^a of bar 1^a, corresponding to teeth 2 of the corresponding bar 1 of Figure 1, will be reversed, and bar 1^a will be provided with a single oppositely facing tooth 2^b, for engagement by 20 the wedge key 9 of the bar 1 adjacent the wall, the notch 2^b being disposed close to the adjacent extremity of bar 1^a. As in this arrangement, the edge of bar 1^a containing the teeth 2^a crosses the lower bar 1, it is necessary 25 to provide two keys to secure said bars in such crossed relation, and to carry said keys a clip 13 is provided. The clip is U-shaped in edge view to provide a passage 15 for the lower bar 1, and one wall of the clip is provided 30 with a vertical channel or passage 16 to accommodate the bar 1^a. The clip is provided with vertical slots 17 to accommodate a vertically-disposed wedge key 18, and a horizontal slot 19 to accommodate a horizontally 35 arranged wedge key 20. When the bars are preliminarily tightened in any suitable manner, the wedge keys are driven home as hereinbefore described with respect to wedge keys 9, so that the key 18 shall engage a notch or 40 tooth of bar 1, and the key 20 shall engage a notch or tooth of the bar 1^a, both bars being thus forced into clamping relation with the 45 enclosed form F. The form may therefore be clamped firmly at all sides provided there

is sufficient space between it and the wall to 50 accommodate the bar 1 adjacent to and parallel with the wall, and the end of the crossing bar 1 projecting from the first-named bar toward said wall.

From the above description, it will be apparent that I have produced concrete form column clamping appliances which may be employed efficiently wherever a column is to be erected, and which may be modified in minor particulars in other respects than those 60 mentioned, within the spirit and scope of the appended claims.

I claim:

1. In a concrete form column clamp, a flat bar formed with a series of teeth along one 65 of its side edges and bifurcated at one of its ends, the members of the bifurcated end being formed with alined openings, and a wedge-shaped locking key carried by said alined openings in the bifurcated end and at right 70 angles thereto.

2. In a concrete form column clamp, crossed flat bars arranged rectangularly and each bifurcated at one of its ends and formed with a series of teeth along one of its side 75 edges, the members of the bifurcated end being formed with alined openings, and tapered locking keys slidingly received in the openings in the bifurcated ends of the clamp bars and extending at right angles to the bifurcations thereof, one edge of said wedge key being adapted for engagement with the teeth of an adjacent clamp bar.

3. In a concrete form clamp, a series of crossed bars arranged angularly and adapted 85 to enclose and flatly engage the sides of a corresponding form, a pair of the bars having their outer edges toothed; a clip slidingly receiving said crossed pair of toothed bars and provided with slots extending parallel with 90 said bars respectively, and wedge-shaped keys fitting in said slots and adapted to engage teeth of said pair of bars and to force said bars inwardly against the adjacent or corresponding sides of the form.

In witness whereof I hereunto affix my signature.

GEORGE F. NEWTON.
